(57) **CLAIM**

I claim, the ornamental design for a toy projectile, as shown and described.

DESCRIPTION

FIG. 1 is a perspective view of an embodiment of the invention;

FIG. 2 is another perspective view of the embodiment of FIG. 1;

FIG. 3 is a side view of the embodiment of FIG. 1;

FIG. 4 is a rear view of the embodiment of FIG. 1;

FIG. 5 is a front view of the embodiment of FIG. 1; and,

FIG. 6 is another side view of the embodiment of FIG. 1. The broken lines shown in FIG. 4 depict unclaimed environmental subject matter.

1 Claim, 1 Drawing Sheet
